UNITED STATES PATENT OFFICE.

THOMAS SERVICE, OF BETHLEHEM, PENNSYLVANIA.

OIL-BURNING-FURNACE FRONT.

Application filed June 11, 1920. Serial No. 388,172.

To all whom it may concern:

Be it known that I, THOMAS SERVICE, a citizen of the United States, residing at Bethlehem, in the county of Northampton, State of Pennsylvania, have invented new and useful Oil-Burning-Furnace Fronts, of which the following is a specification.

It is essential in order to secure the best results in an oil burning furnace that the air to promote combustion be admitted around the entire periphery of the burner, or the flame cone thereof without eddy currents due to narrow openings, when the air inlets are partially open, and the air going to said flame cone, should travel in a continuous annular stream. It is also desirable that the air be given a whirling motion to insure an effective commingling with the atomized oil and vapor and that the air travel in short, direct and guided paths to said flame cone under all degrees of openings. There should also be provided a positive control of the quantity of air fed to the burner, in conjunction with a fine degree of regulation, and to the above ends my invention consists of a novel construction of an oil burning furnace front suitable for use with both natural and forced draft embodying generally preferably three component parts, (a) a casing adapted to be fastened directly to the boiler or furnace front and carrying the air inlet devices, comprising a novel construction and arrangement of vanes between which air is admitted either by natural draft or by a forced draft to the atomized fuel, said vanes being so positioned as to give the incoming air a whirling motion in the same or opposite directions with respect to the atomized fuel, thereby insuring its proper commingling with the atomized particles of oil or other hydrocarbon fuel, (b) a novel construction of valve pot capable of being longitudinally adjusted within said casing and (c) a novel burner supporting bracket and its adjuncts.

It further consists of a novel construction of an outer casing adapted to be secured directly to the boiler or furnace front and to enclose an adjustable valve pot, whereby a positive control for the quantity of air fed to the burner or flame cone with a fine degree of regulation is provided, and provision is further made for shutting off completely the air supply when the burner is shut down.

It further consists of a novel construction of a casing having novel means for admitting air around the entire periphery thereof, the air being admitted axially of the burner and travelling in a continuous annular stream, in a whirling direction and in short, direct and guided paths to the flame cone, whereby a more complete combustion is effected than heretofore.

It further consists of a novel construction of a casing provided with an annular front valve seat and with annularly arranged vanes, whereby the air is given a whirling motion in the same or opposite direction to that of the atomized fuel, to ensure a better commingling with the atomized oil and vapour.

It further consists of a novel construction of a valve pot having its forward end of conical shape and coating with an annular valve seat on the outer enclosing casing.

It further consists of a novel manner of mounting and actuating the valve pot with respect to the outer casing and the burner bracket and its adjuncts.

It further consists of a novel actuating mechanism for said valve pot and its adjuncts, whereby I secure a positive control of the amount of air fed to the burner, with precise means of regulating such amount to the rate of fuel consumption.

It further consists of a novel construction of a burner supporting bracket upon which, the burner and its adjuncts and the valve pot actuating mechanism are supported.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a front elevation of an oil burning furnace front, embodying my invention, showing particularly the burner supporting bracket, the valve pot actuating mechanism and its supporting means.

Figure 2 represents a top plan view of Figure 1, a portion of the casing being

110

broken away to show the manner of actuating the valve pot.

Figure 3 represents a section on the line 3—3 of Figure 1, certain of the parts being shown in elevation.

Similar numerals of reference indicate corresponding parts. Referring to the drawings:—

1 designates a casing which is adapted to 10 be fastened directly to the boiler or furnace front in any suitable manner, the same comprising the rear shell 2, the forward annular portion or wall 5, having the annular beveled portion 3, which has the function 15 of an annular valve seat and the rear annular portion or wall 6 and the intermediate tangentially arranged vanes 4, which are located or formed between the annular walls or portions 5 and 6, the general arrangement 20 or collocation of said vanes, through which the air is admitted to the burner or flame cone thereof being understood from Figures 2 and 3.

The forward annular valve seat 3 may 25 be formed upon the annular wall 5, which has its inner portion beveled to conform to the beveled valvular portion 7 of the valve pot, the latter comprising the rear wall 8 and the annular wall 9, from which said 30 conical valvular member 7 projects, it being understood that the contacting surfaces between said valve pot and casing are machined to fit and that the walls 9 and 7 of said valve pot constitute a sliding or adjustable damper and control the inlet of the air through the vanes 4.

The vanes 4 as will be understood from Figure 1, are tangentially arranged so as to give the incoming air a whirling motion 40 in the same or opposite direction, as the tangential motion of the particles of finely divided oil emitted from the atomizer 10, to which the oil is admitted by the supply pipe 11, which may be centered in the air tube 12 by the spider 13, the inner end of said air pipe having the cone 14 attached thereto, whose function is that of a shield to prevent direct blasts of air on the flame and also to prevent carbonization of oil on the burner 50 tips.

I have deemed it unnecessary to describe in detail the atomizer 10, as any suitable atomizer may be employed.

15 designates a conduit, whereby forced 55 draft may be directed to the vanes 4 when desired, it being apparent that my novel device is equally adapted to a forced or natural draft.

17 designates a transverse cross bar or 60 burner supporting bracket having its ends bolted or otherwise secured either to the flange 18 (or bosses thereon) of the shell 5, (see Figure 1) said burner supporting bracket having the opening or passage 19, 65 for the reception of the air tube 12, and

having the forward and rearward extensions 20 and 21, in which the set screws 22 are located, whereby said air tube may be adjusted longitudinally and locked in any desired position, it being apparent that said extensions 20 and 21 form an elongated bearing for supporting said air tube, burner and their adjuncts, and that the entire outer periphery of the extension 20, in conjunction with the inner wall 23 of the shell 2 75 form guiding bearings for the valve pot 8, as it is adjusted forwardly and backwardly, by the mechanism now to be described, reference being had to Figures 1 and 2, wherein I have shown a preferred 80 form of the valve pot adjusting devices, although it is evident that other equivalent constructions may be employed, without departing from the spirit of my invention.

24 designates a rack bar having its inner end secured to the rear wall 8 of the valve pot, by any suitable means, as will be understood from Figure 2 and its outer end passing through a hole or bearing 25 in the cross bar or burner supporting bracket 17 90 and being supported therein, the underside of said bar having rack teeth 26 thereon in mesh with the pinion 27, which is mounted on the spindle or shaft 28, which has its inner end 29 stepped into the boss or bearing 95 30 as seen in Figure 1 and its outer portion guided in the lug or bracket 31 and provided with the hand wheel 32, whereby the pinion 27 can be readily rotated and the rack and valve pot reciprocated as a unit according to requirements. The collar 33 on the spindle 28 retains the spindle in its proper position, so that the pinion and rack properly mesh.

The rear wall 8 of the valve pot has a 105 peep hole 33 therein, which is closed by the door 34, the latter having the lighting torch hole 35 therein, and said door being opened and closed according to requirements by the chain 36.

It is well known to those skilled in the art that when the burner is not lighted, oil is liable to drip from the oil burners or oil valves, when they have not been tightly closed and by my invention, I provide a 115 means for catching said oil and conveying it outside of the combustion chamber through a leak off or drip having a plug 37 as seen in Figure 3, whereby any drip can be readily seen and any trouble of this character readily remedied. This prevents explosions when starting or relighting boilers from oil which may have leaked into the combustion chamber during a shut down.

While I have shown my novel casing 1 as 125 attached to the furnace front 38, by means of bolts 39 passing through the annular wall 5, these parts may be assembled in other equivalent means without departing from the spirit of my invention.

I preferably stiffen and reinforce the valve pot by the provision of the ribs 40, which are preferably six in number, and comprise the upright portion 41, which can 5 be cast on the wall 8, the horizontal portion 42, cast on the annular wall 9 and the forward portion 43, cast on the wall 7, whereby the valve pot body, comprising the walls 8, 9 and 7 is effectively stiffened and reinforced. These stiffening ribs may be 10 omitted, however.

The operation is as follows:—

Before the boiler is lighted, the valve pot should be in a nearly closed position or adjusted slightly to the right of the position seen in Figure 3 thereby decreasing the danger of flarebacks. The burner having been lighted, the desired adjustment of the valve pot can be effected towards the position seen 15 in dotted lines in Figure 3, by rotating the hand wheel 32, it being apparent that the rotation of said hand wheel rotates the pinion 27, which by its engagement with the rack teeth 26 will cause the valve pot to 20 move in the desired direction to the desired extent.

The valve pot having its cylindrical wall 9 functioning as a damper is shown in Figure 3 in full lines in its extreme left hand 30 or closed position and is shown in dotted lines in its extreme right hand or open position, and it will be apparent that the axial longitudinal movement of the valve pot is effected through the rotation of the hand 35 wheel 32 thus giving a finer degree of adjustment and a positive method of locking in any position.

It will be apparent that a certain amount of atmospheric air is drawn in through the 40 air tube 12 and commingled with the hydrocarbon or other fuel discharged through the atomizer 10, and when the valve pot is moved to the right of the closed position seen in Figure 3, so as to unseat the valvular member 7 from its seat 3 on the wall 5, it will be apparent that a predetermined amount of air will be admitted through the 45 vanes 4 in a whirling motion to the desired points, and will be effectively commingled with the atomized oil and vapour, the air going to the flame cone in a continuous annular stream and there being no gaps.

It will be further apparent that the incoming air has short, direct, and guided 50 paths to the flame cone through all degrees of openings, and there is, upon the proper manipulation of the valve pot a positive control of the quantity of air to the burner through the vanes 4 with a fine degree of 55 regulation.

When the burner is shut down, it will be 60 apparent that the air supply can be completely shut off therefrom by advancing the valve pot into the closed position seen in full lines in Figure 3, and it will be further ap-

parent that all direct radiation from the flame cone to the fire room is prevented by the vanes 4 in the air inlet and by the valve pot. By admitting air around the entire periphery of the casing 1, as will be understood from Figure 1, it will be apparent that less eddy currents, due to narrow openings, when the valve pot is partially opened, are created, and the air going to the flame cone will travel in a continuous annular stream. 75

It will be further apparent that my novel construction of furnace front may be used without alteration with natural draft or in a closed fire room under pressure with forced draft through the ducts or conduits 15. 80

When my novel device is used with a forced draft, the quantity of air is obviously regulated by the position of the valve pot and when said valve pot is in its closed position seen in Figure 3, all air to the burner 85 is shut off and the duct connection 15 leading from the blower (not shown) is closed, thereby decreasing the quantity of air the blower has to discharge.

It will be apparent that upon the removal 90 of the burner supporting bracket, the valve pot and the various burner parts are readily disassembled or dismantled and access to the combustion chamber 44 is obtained through a free opening, which is in practice twenty 95 inches or more in diameter.

It will be apparent that by the inclination or positioning of the vanes 4, as will be understood from Figure 1, the incoming air is given a whirling or tangential motion, thus 100 insuring an intimate commingling with the atomized fuel, and it is obvious that said vanes may be collocated with the burner so as to give the incoming air a whirling motion in the same direction as the tangential 105 motion of the atomized fuel, or, if desired, the vanes may be so collocated that the incoming air will have a direction or a whirling motion opposite to that imparted to the atomized oil, whereby in either case a very 110 intimate commingling of the atomized fuel and air will be effected.

It will be apparent that while I have shown the preferred manner of assembling the casing, valve pot and burner supporting bracket, which will be found to be very efficient and satisfactory in practice, that slight changes may be made in the manner of assembling these elements, without departing from the spirit of my invention. 115

It will now be apparent that I have devised a novel and useful oil burning furnace front, which embodies the features of advantage enumerated as desirable in the statement of the invention and the above 125 description, and while I have, in the present instance, shown and described a preferred embodiment thereof which will give in practice satisfactory and reliable results, it is to be understood that the same is sus- 130

ceptible of modification in various particulars without departing from the spirit or scope of the invention or sacrificing any of its advantages.

5 Having thus described my invention, what I claim as new and desire to secure by Letters Patent, is:

1. In a device of the character stated, a casing adapted to be attached to a furnace front, and having an annular valve seat, and annularly tangentially arranged vanes, a valve pot slidably mounted in said casing, a 10 conical valvular forward end portion on said valve pot adapted to engage said seat when said valve pot is in its extreme forward position, and actuating means for said valve pot, comprising a rack attached thereto, a pinion in mesh with said rack, a transverse supporting bracket secured to the outer portion 15 of said casing and a spindle rotatably mounted in said bracket on which said pinion is mounted.

2. In a device of the character stated, a valve pot comprising a cylindrical body portion having a rear wall, with an opening therein, and a front conical valvular member, said valve pot being provided with actuating means, and its rear wall having a peep hole therein, said peep hole being 20 closed by a door.

3. In a device of the character stated, a casing adapted to be attached to a furnace front and having an annular front valve seat, annularly, tangentially arranged vanes, a valve pot slidably mounted in said casing, a burner supporting bracket mounted on said casing, an air tube supported by said bracket and having a cone on the inner end thereof, an oil atomizer supported within said cone, 35 and actuating means for said valve pot comprising a rack attached thereto, a pinion in mesh with said rack, a spindle having its inner end stepped in a boss on said bracket and carrying said pinion and its outer end 40 supported in a lug carried by said bracket, the outer end of said spindle having a hand wheel mounted thereon.

4. As an improved article of manufacture, a burner supporting bracket comprising a transverse member having a passage through 50 its central portion and forward and rearward extensions adapted to receive an air tube, oil burner and their adjuncts, a boss on said bracket having a stepped bearing 55 therein, a lug on said bracket in which said spindle has its bearing, and an opening in said bracket for guiding the valve pot rack bar.

5. In a device of the character stated, a 60 casing having an annular valve seat and a series of annular, tangentially arranged vanes, a valve pot located in said casing and having a forward conical valvular portion adapted to coact with said valve seat, a 65 burner supporting bracket mounted on said

casing and having a forward extension on which the rear wall of said valve pot is supported and guided, an air tube also supported in said extension and having a cone on the inner end thereof, oil atomizing devices carried by said air tube, a rack extending rearwardly from said valve pot, a spindle supported on said burner bracket and having a pinion on the inner end thereof in mesh with said rack, and a hand wheel on 70 the outer end of said spindle for actuating said spindle, pinion, rack and valve pot in unison.

6. In a device of the character stated, a casing having a front annular valve seat, 80 and a series of annular, tangentially arranged vanes, a valve pot located in said casing and having a forward conical valvular portion adapted to coact with said valve seat, a burner supporting bracket mounted 85 on said casing and having a forward extension on which the rear wall of said valve pot is supported and guided, an air tube also supported in said extension and having a cone on the inner end thereof, oil atomizing devices carried by said air tube, a rack extending rearwardly from said valve pot, a spindle supported in said burner bracket and having a pinion on the inner end thereof 90 in mesh with said rack, a hand wheel on the outer end of said spindle for actuating said spindle, pinion, rack and valve pot in unison, 95 internal stiffening ribs for said valve pot, an oil leak-off for said valve pot, and a peep hole in the rear wall of said valve pot provided with a door for closing the same, said door having a torch opening therein.

7. In a device of the character stated, a casing having front and rear annular walls and a rearwardly projecting portion, inclined vanes annularly arranged between said walls, an annular valve seat on said front wall, a valve pot contained within said casing and having its forward portion adapted to coact with said valve seat, a burner supporting bracket mounted on the rearwardly projecting portion of said casing, an air tube supported in said bracket, a cone attached to the inner end of said air tube, oil atomizing devices located within said air tube, a rack projecting rearwardly from said valve pot and guided in said burner supporting bracket, a spindle having bearings in said bracket, a pinion carried by said spindle and engaging said rack, and a hand wheel for operating said spindle.

8. In a device of the character stated, a casing adapted for forced or natural draft and adapted to be attached to a furnace front and having an annular valve seat, annularly, tangentially arranged vanes in said casing, a valve pot slidably mounted in said casing, actuating means for said valve pot comprising a rack attached thereto, a pinion in mesh with said rack, a spindle on 120

- which said pinion is mounted, a hand wheel 5 on said spindle, and a burner supporting bracket carried by said casing in which said rack is guided and on which said spindle is mounted.
9. In a device of the character stated, a casing adapted to be attached to a furnace front and having a front annular valve seat, annularly, tangentially arranged vanes in 10 said casing, a valve pot slidingly mounted in said casing, actuating means for said valve pot comprising a rack attached thereto, a pinion in mesh with said rack, a spindle on which said pinion is mounted, a hand wheel 15 on said spindle, a burner supporting bracket secured to said casing in which said rack is guided and on which said spindle is mounted, an air tube supported in said bracket, a cone on the inner end of said air tube, and oil atomizing devices located 20 within said cone.
10. In a device of the character stated, a casing adapted for forced or natural draft and adapted to be attached to a furnace front and having an annular valve seat, air 25 inlets in said casing, a valve pot slidingly mounted in said casing and having a forward conical valvular portion adapted to engage said seat, a bracket attached to the rear of said casing, a rack attached to said 30 valve pot and slidingly mounted in said bracket, a spindle rotatably mounted on said bracket and a pinion on said spindle in mesh with said rack.
